UNITED STATES PATENT OFFICE.

FRANK E. BECKA, OF CLEVELAND, OHIO.

PORTABLE LAMP FOR SEWING MACHINES, ETC.

Application filed July 16, 1924. Serial No. 726,350.

To all whom it may concern:

Be it known that I, FRANK E. BECKA, a citizen of the United States, residing at Cleveland, in the county of Cuyahoga and State of Ohio, have invented certain new and useful Improvements in Portable Lamps for Sewing Machines, Etc., of which the following is a specification.

This invention relates to improvements in portable lamps and particularly to a type designed for attachment to a sewing machine in such a position as to direct light rays upon the article being stitched by the machine.

It is an object of this invention to provide a light which may be securely, yet removably attached to the head of a sewing machine, this light being shiftable to several different positions and constructed so that any of these positions may be maintained without possibility of it accidentally shifting due to vibration of the machine or other causes.

It is likewise an object to provide a portable lamp which may well be used in connection with other machines and devices aside from the sewing machine, association with which is the primary object.

Other objects will be in part obvious and in part pointed out hereinafter.

In order that the invention and its mode of operation may be readily understood by persons skilled in the art, I have in the accompanying illustrative drawings, and in the following detailed description based thereon set out one possible embodiment of the same.

Figure 1 is a side elevation of a sewing machine head, this portable lamp being illustrated in operative position;

Figure 2 is a detail elevation of the portable lamp;

Figure 3 is a detail elevation taken at right angles to the illustration in Figure 2, and

Figure 4 is a sectional view taken substantially on the line 4-4 of Figure 2.

Having more particular reference to the drawings throughout which similar characters of reference designate like parts this invention may be stated as comprising a socket 5 mounting the usual switch finger piece 6, and having a rearwardly extending sleeve 7, through which the conductor 8 is led to the socket. Arranged upon the forward end of this socket and rigidly con-

nected thereto is a tubular metal shield 9, which serves as a means for concentrating the light rays upon any particular point. This shield has one side portion cut away as shown in Figure 2 so the light rays may be projected therefrom. The forward end of this shield 9 is closed by means of a removable flanged cap member 10, the rear end being closed in a similar manner except that the cap member 11 is welded or otherwise rigidly connected to shield and carries a lamp supporting portion 12.

The sleeve 7 heretofore referred to is rotatable on a neck portion 13, so the lamp and its shield may be adjusted to project the light rays in the desired direction. In order to retain this sleeve 7 at any adjusted point I provide a set screw 14 which binds against the neck 13, as shown in Figure 4. Diametrically opposite this set screw and integrally formed upon the sleeve 7 is a threaded stud 15 which mounts at its other end a wing nut 16 whose purpose will be apparent.

In order that this lamp may be reliably attached to a sewing machine head or other support I provide a substantially U-shaped spring metal clip 17, formed of a single strip of metal bent upon itself as at 18, and being apertured at this point to receive the aforementioned threaded stud 15. From this folded point the arms 19 are curved outwardly, then inwardly, and at the point 20 are arranged in parallel relation, the end portions being folded or bent inwardly upon themselves and provided with transversely alined openings designed to receive securing or locking bolts 21. In application of this lamp to a sewing machine the bolt 21 is removed: the arms 19 are slipped over the sewing machine head and the bolt 21 is inserted into the openings at the end of the arms and upon tightening the wing nut reliable connection is effected. Should the respective position of the opening in the shield 9 be incorrect, the set screw 14 may be loosened so as to permit shifting of the shield and its associated parts with respect to the position of the clip. Further adjustment is permitted through loosening the wing nut 16 carried by the sleeve, this operation permitting horizontal swinging of the lamp shield and its associated parts with respect to the supporting clip.

Heretofore certain types of lamps have been designed for use about sewing ma-

chines and the like but they have been unsatisfactory because of the fact that they cannot be accurately adjusted to concentrate the light rays upon the desired point 5 and the adjustment which is possible cannot be maintained due to the absence of the means for preventing movement resulting from the vibration of the machine. These objections are entirely overcome through 10 the use of the structure as herein brought out.

I claim:

1. The combination with a sewing machine head of a substantially U-shaped clip 15 engageable with the head, said clip having a flat apertured arm between its ends, a socket, a neck carried by said socket, a sleeve rotatably mounted on said neck, a stud carried by said sleeve and projecting through the apertures, means for locking the arm in an adjusted position with respect to the neck, an elongated tubular shield carried by the socket and having an opening in one side, and an electric lamp arranged

in said shield and connected to the socket. 25

2. A portable lamp of the character described comprising a socket, an elongated tubular shield axially aligned with said socket and having an opening in one side, an electric lamp arranged in said shield 30 and connected to the socket, a neck axially aligned with the socket and extending therefrom at the end opposite said shield, a sleeve loosely mounted upon the neck and carrying a threaded stud, a strip of sheet metal 35 folded upon itself and forming an arm, said arm being apertured to fit over the stud, a pair of outwardly curved arms extending from a point adjacent the apertured arm and having a pair of transversely aligned 40 openings, a bolt receivable in said openings and a set screw carried by said sleeve whereby to permit adjustment of the shield and socket with respect to the clip.

In testimony whereof, I affix my signature. 45

FRANK E. BECKA.
